UNITED STATES PATENT OFFICE.

CHARLES S. TAYLOR, OF MOUNT VERNON, WASHINGTON, ASSIGNOR TO FREDERICK W. CRAM AND J. W. JOHNSON, BOTH OF MOUNT VERNON, WASHINGTON.

HINGE FOR SILO-DOORS.

1,193,204.

Specification of Letters Patent.

Patented Aug. 1, 1916.

Application filed April 17, 1915. Serial No. 21,946.

To all whom it may concern:

Be it known that I, CHARLES S. TAYLOR, a citizen of the United States of America, and a resident of the city of Mount Vernon, 5 in the county of Skagit and the State of Washington, have invented certain new and useful Improvements in Hinges for Silo-Doors, of which the following is a specification.

10 My invention relates to silo doors and consists of an improved construction of the hinged supporting and controlling members.

15 The object of my invention is to provide a hinge for silo doors which will permit the door being moved bodily inward and then swung about against the inner face of the silo wall alongside the door opening.

20 The scope of my invention will be defined by the claims.

In the accompanying drawings I have shown my invention in the form which is preferred by me.

25 Figure 1 is an exterior face view of the door in closed position. Fig. 2 is a transverse sectional elevation and Fig. 3 a sectional plan of the door in its preliminary open position.

30 The door opening is preferably outlined by frame 2 of iron, the inner faces of which may be made smooth and true. I provide two hinges by which the door is supported at one vertical edge. Each of these hinges is a double hinge, that is consists of two leaves 30 and 31, hinged together by a pin 33. One of these leaves, as 30, swings upon a pin 32 which is supported from the jamb or door casing. The other end of the other leaf 31, engages pin 34 which connects it 35 with the outer face of the door 1, adjacent one edge of the door. The leaf 36 with which the corresponding end of the other swinging leaf 30 is pivoted is secured to the outer part of the door casing.

40 With each of the hinges as above described a controlling member 5 is employed. This consists of a link which is pivoted by one end upon the pin 34 and its other end is fixedly pivoted, as at 50, to the door casing

50 at a point toward the opposite side of the door opening. This point as shown in the drawings is closely adjacent the opposite side of the door opening. It might, however, be located at a less distant point.

55 With the door in closed position, the hinges 3 would lie against the outer face of the door, as is shown in Fig. 1. To open the door it is pushed inward, the leaves 30 and 31 of the hinges swinging into a position illustrated in Figs. 2 and 3. In this position, 60 the door may be swung upon the hinged pivots 34, into fully open position. To facilitate handling the door it may be provided with rings or hand holds, as 6.

65 By the above expedient the hinges may be kept entirely upon the outer surface of the door and casing, leaving the edges of the door and the inner faces of the casing, free of all attachments. Also the angle of inclination of these edge surfaces may be kept 70 small so as to insure a thoroughly tight joint, while permitting a preliminary inner movement of the door bodily before the swinging action commences.

Having thus described my invention what 75 I claim as new, and desire to secure by Letters Patent, is:

1. A hinge support for silo doors comprising two members hinged to each other at one end, and at their other end respectively to a door jamb and to the corresponding door edge, and a third member having hinged connection with the same edge of the door and with a distant fixed point located toward the opposite side of the door 85 opening.

2. A hinge support for silo doors comprising two hinged leaves pivoted to each other and respectively upon the door jamb and upon the door face adjacent the corresponding edge of the door, and a third member having a hinged connection of one end common with the hinged connection of the other member with the door and a fixed pivot support for its opposite end adjacent 95 the opposite door jamb.

3. A hinged support for silo doors comprising a bar pivoted to the door jamb ad-

jacent one edge of the door and extending across the door opening, the door being pivoted to swing upon the other or free end of said bar and a support for the same side 5 of the door permitting a limited movement of this side of the door inward away from the casing.

Signed at Mount Vernon, Washington,
this 8th day of April 1915.

CHARLES S. TAYLOR.
